UNITED STATES PATENT OFFICE.

ALBION W. TOURGEE AND LINSON DE F. JENNINGS, OF MAYVILLE, NEW YORK, ASSIGNEES TO SAID JENNINGS AND S. E. KILBOURN, OF SAME PLACE, AND A. C. KILBOURN, OF ERIE, PENNSYLVANIA.

VEHICLE RUNNING-GEAR.

SPECIFICATION forming part of Letters Patent No. 336,534, dated February 16, 1886.

Application filed June 2, 1885. Serial No. 167,393. (No model.)

To all whom it may concern:

Be it known that we, ALBION W. TOURGEE and LINSON DE F. JENNINGS, citizens of the United States, residing at Mayville, in the county of Chautauqua and State of New York, have invented certain new and useful Improvements in Vehicle Running-Gear; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention has for its object to provide an improved and novel construction of vehicle running-gear, whereby lightness and utility are combined with great strength and durability, and the ease of repair and interchangeability of parts promoted in the simplest and best possible manner; and our improvements consist, essentially, in forming the several parts from sheet-steel struck up into the desired shape, or drawn out in tubular form, and in connecting said parts by a series of steel couplings, all as will be hereinafter fully described, and pointed out in the claims.

In the accompanying drawings, Figure 1 represents a top plan view of the running-gear, with parts in section to more fully show the construction; Fig. 2, a sectional view of the axle, and Fig. 3 an enlarged detail sectional view.

Similar letters of reference occurring on the several figures indicate like parts.

Referring to the drawings, A represents the perch or connecting-pole formed of one continuous cylinder of drawn steel or steel struck up in a cylindrical or oval form and threaded at each end for engagement and connection with the central T-shaped couplings, B B', upon the front and rear axles, C C', as fully shown in Fig. 1.

The T-shaped coupling B, at the center of the front axle, C, has forged upon it the metallic head-block a, which is suitably perforated to receive the coupling-pin or king-bolt b.

At proper distances upon the perch or connecting-pole A is disposed the threaded collar-couplings D D', the one, D', of which engages with the threads upon the outer surface of the inner ends of the braces E E', to secure the same to the perch or connecting-pole, said braces being preferably formed of the one-half of a steel cylinder split lengthwise, but which may be struck up from steel sheet metal into an oval or half-cylindrical form, the rear ends of said braces being secured in a corresponding manner to the rear axle, C', by the threaded collar-couplings F F', as shown.

N represents a metallic strap extending from the collar-coupling D, by which it is attached to the perch A, to the upper end of the coupling-pin or king-bolt b, upon which it is held by means of a suitable nut working upon the screw-threads at the top of the bolt.

The front and rear axles, C C', are each preferably composed of two sections of tubular or drawn steel, connected together at the center by the T-shaped couplings B B', and having their outer ends threaded to engage with the screw-caps I, upon which are forged threaded arms or extensions e, designed to screw into the spindle.

The threaded couplings d d' upon the front axle, C, engage with the traction-lugs d'', the inner ends of said couplings being made somewhat larger than the outer, so as to embrace between them and the surface of the axle the said traction-lugs d''. This traction-lug is a semi-tubular piece of steel fitting exactly the curve of the axle, very thin at its outer end and thick at the inner end, and having forged upon said inner end a bolt of the shape and character of the ordinary lugs used to attach the shafts or pole to the axle.

By means of our improvements the several parts of the running-gear can be taken apart with an ordinary pipe-wrench in a short time, and as readily put together, thereby permitting of the easy removal of a broken part and the substitution of a new one in its place without the aid of skilled labor.

Having thus described our invention, what we claim as new, and desire to secure by Letters Patent, is—

1. The herein described vehicle running-gear, consisting of the perch or connecting-pole A and axles C C', formed, as described, of drawn or tubular steel, connected together by the steel T-shaped couplings B B', and provided with the braces E E', collar-couplings D D' and F F', brace N, head-block *a*, and king-bolt *b*, all constructed substantially in the manner shown, and for the purpose specified.
2. The axles C C', constructed, as described, of drawn or tubular steel, in two parts or sections united at the center by the T-shaped couplings B B', and provided at their outer ends with the steel screw-caps I, having threaded arms or extensions *e* forged thereon, substantially as described, and for the purpose specified.
3. The T-shaped coupling B, having the head-block *a* and king-bolt *b*, formed solid therewith, in combination with the axle C, perch or connecting-pole A, and metallic strap N, substantially as shown, and for the purpose specified.
4. The threaded collar-couplings *d d'* and *d' d''*, in combination with the axle C, substantially as and for the purpose specified.

In testimony whereof we affix our signatures in presence of two witnesses.

ALBION W. TOURGEE.
LINSON DE F. JENNINGS.
